UNITED STATES PATENT OFFICE.

WILLIAM CLIFTON CUTLER, OF NORTH GLENDALE, CALIFORNIA.

CARD-RECEPTACLE.

1,248,822.

Specification of Letters Patent.

Patented Dec. 4, 1917.

Application filed December 15, 1916. Serial No. 137,162.

To all whom it may concern:

Be it known that I, WILLIAM CLIFTON CUTLER, a citizen of the United States, residing at North Glendale, in the county of Los Angeles and State of California, have invented new and useful Improvements in Card-Receptacles, of which the following is a specification.

My invention relates to improvements in card receptacles in which a mechanism is provided for shifting the cards out of the receptacle one by one to the last card in the receptacle; and the objects of my improvements are, to provide a receptacle with means which will automatically deliver one card at a time by a short movement or push of a thumb or finger; to provide means in such receptacle indicating when the receptacle is empty; to provide means in such receptacle for shifting always just one card out of the receptacle; to simplify the construction of such receptacle; the invention consisting in the construction, combination and arrangement of devices hereafter more fully described and claimed, and illustrated in the accompanying drawing, in which—

Figure 1 is a vertical longitudinal section of the device.

Fig. 2 is a cross-section through the lower part or body of the receptacle on line 2—2 of Fig. 1.

Fig. 3 is the top view of the spring, disposed in the receptacle for lifting the cards ready to be shifted out of the receptacle.

Fig. 4 is the top view of the cover for the receptacle.

Fig. 5 is a cross-section of the cover on line 5—5 of Fig. 4.

Fig. 6 is the sliding plate with the fulcrum and shifting bar in end view placed in the slot of the cover plate, of which a portion is shown in section.

Fig. 7 is the sliding plate with the fulcrum and shifting bar of Fig. 6 in plan view seen from under side.

Fig. 8 is a part of the shifting bar in side view.

Fig. 9 is the end view of the bar in Fig. 8.

Similar numbers refer to similar parts throughout the several views.

The receptacle 1 is preferably made of one piece of material, steel, brass, aluminum, or any other suitable for such purpose.

The receptacle consisting of the bottom plate 2, the two side plates 3 and the end plates 4 and 5. The end plates extend be-

yond the side plates as indicated at 6, see Fig. 2, forming the guide and engaging members between the cover plate 7 and the receptacle. The end plate 4 is furthermore 60 extended above the upper edge of the side plates as indicated at 8 closing that end of the receptacle entirely, while the end plate 5 is terminated a suitable distance below the top plate, leaving a slot 9 for the cards to 65 escape when pushed out of the receptacle. As the receptacle is provided with the extensions mentioned above, the cover is only bent on the two sides 10, the whole cover fitting between the extensions of the end plates 70 4 and 5 of the receptacle, the two bent sides of the cover fitting over the two sides 3 of the receptacle. A spring 11 is disposed in the receptacle for bringing the cards up to the top. Extension ends 12 on the spring are 75 provided for holding the spring in the desired position, the extension ends fitting in the recesses 13 in the side plates 3, see Fig. 2. The projection 14 on the spring forms the stop for the shifting bar 15, when the 80 receptacle is empty, the dotted lines 16 indicating the position of the shifting bar in engagement with the projection on the spring. The shifting bar 15 is secured to the fulcrum 17, which is pivotally mounted 85 on the pin 18. A sliding plate 19, see Figs. 6 and 7, is cut in about the middle to provide material for the lugs 20, in which the pin 18 is supported. The rest of the material, provided by the cut, is used for the lugs 21, 90 which are folded to fit slidably over the material of the cover plate, as shown in Figs. 1 and 6. By bending the lugs as illustrated, a slot 22 is provided for the fulcrum 17. The pin 18 is loosely disposed through 95 the lugs 20 and the fulcrum 17 and not riveted in, as the pin is in a position between the material of the top plate 7, as will be clear from the Figs. 1 and 6. The recess 23 in the top plate, see Figs. 4 and 5, is provided for the sliding plate 19, and the slot 24 fits over the lugs, which are slidably mounted therein. The shifting bar 15 is provided with a catching needle 25, see Figs. 8 and 9, and to prevent the needle from 100 going in too far into the cards, a shoulder 26 is provided near the point of the needle.

The operation is as follows:—

The receptacle being filled with cards, the fulcrum 17, mounted in the sliding plate 19, 110 is pushed along the slot 24 in the cover plate 7 toward the slot 9 formed between the

receptacle and the cover as indicated in Fig. 1. The fulcrum, being pivoted on the pin 19, will naturally turn over toward the slotted front of the receptacle when pushed upon by a finger or thumb, and the shifting bar 15, being secured to the fulcrum, is naturally pressed down upon the cards in the receptacle. A further pushing on the fulcrum 17 causes the needle 25 to stick into the top one of the cards placed in the receptacle, and a still further pushing causes this top card to slip through the slot 9 out of the receptacle.

This operation can be repeated until all 15 cards are pushed out of the receptacle, when the shifting bar 15 will engage with the stop 14 on the spring 11, this indicating that the receptacle is empty, as described.

Having thus described my invention, I 20 claim:—

1. In a card receptacle of the type described comprising a body part of substantial rectangular bottom with two side plates and two end plates, and a cover part having 25 two side plates so as to fit over the side plates of the body part slidingly; the end plates of the body part being provided with extension ends projecting beyond the side plates on the body part so as to prevent a 30 slipping of the cover part endwise when engaged over the body part.

2. A card receptacle of the type described consisting of a body part having a plain bottom, two side plates, and two end plates; 35 both end plates having extension ends projecting sidewise beyond the side plates; a cover fitting over the side plates of the body part and fitting also slidingly between the extension ends of the end plates of the body 40 in an up and downward direction; one end plate projecting also upwardly beyond the upper edge of the side plates of the body part to the extent of the thickness of the top plate forming an entirely closed box 45 on that end while the other end plate terminates a suitable distance below the top plate forming a slot between this end plate and the top plate of the size adapted to allow the discharge of one card at a time out 50 of the receptacle.

3. In a card receptacle of the type de-

scribed comprising a body part of substantial rectangular bottom with two side plates and two end plates, and a cover part having two side plates so as to fit over the side 55 plates of the body part slidingly, the end plates having extension ends to the extent of the thickness of the cover plate so as to engage the cover plate endwise slidingly; shifting means provided on the cover part 60 lengthwise to the receptacle so as to allow an ejecting of cards out of the receptacle while the cover remains engaged between the extension ends of the end plates of the body part. 65

4. In a card receptacle of the type described a spring disposed at the bottom of the receptacle with springing capacity toward the top of the receptacle having a stop formed at a suitable place in the top surface 70 of the spring, and a card shifting mechanism mounted on the top of the receptacle projecting into the receptacle toward the spring so as to engage with the stop on the spring when no card is in the receptacle 75 for preventing the shifting means from being shifted.

5. A card receptacle comprising a body part of substantially rectangular bottom with two side plates and two end plates, the end plates projecting side-wise beyond the side plates; a cover part having two side plates so as to fit over the side plates of the body part slidingly between the extension ends of the end plates, the cover part being 80 provided with a rectangular recess and a slot within the recess; a shifting plate slidingly mounted within the recess of the cover part having lugs projecting through the slot in the cover slidingly engaging the shifting 85 plate with the cover, the lugs forming at the same time attaching means for card shifting means in such receptacles; and card ejecting means pivotally connected to the lugs in the shifting plate on the cover. 90 95

In testimony whereof I hereunto affix my signature in the presence of two witnesses:
